UNITED STATES PATENT OFFICE.

RICHMOND ROCHESTER, JR., OF CHICAGO, ILLINOIS, ASSIGNOR TO AUTOMATIC ELECTRIC BOILER CO., OF CHICAGO, ILLINOIS, A CORPORATION OF DELAWARE.

HEATING APPARATUS.

Application filed June 24, 1926. Serial No. 118,259.

My invention relates to heating apparatus and has among its other objects the production of apparatus of the kind described, which is compact, convenient, reliable, durable, efficient and satisfactory for use wherever found applicable.

A particular object of the invention is to provide improved apparatus of the kind described wherein water is heated by means comprising electrodes immersed therein.

Another particular object of the invention is to provide improved apparatus of the kind described which will be substantially automatic in its operation.

Still another particular object of the invention is to provide improved electrodes for apparatus of the kind described.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a section taken through a building wherein apparatus embodying the invention is installed;

Fig. 2 is a side elevation of my improved heating unit;

Fig. 3 is a plan elevation of the improved heating unit shown in Fig. 2;

Fig. 4 is a section taken on line 4—4 of Fig. 3;

Fig. 5 is an enlarged side elevation of my improved electrodes;

Fig. 6 is an end elevation of the improved electrodes;

Fig. 7 is a plan view of the improved electrodes; and

Fig. 8 is an enlarged section taken on line 8—8 of Fig. 4.

Referring for the present to Fig. 1 wherein I have shown apparatus embodying one form of the invention installed in a building, the reference character 10 designates generally my improved heating unit wherein water is heated by means comprising electrodes hereinafter described. The water heated in the heating unit 10 passes there-

from through a pipe 11 which communicates with branch pipes 13 in the upper part of the building. Depending from the branch pipes 13 are a plurality of pipes 15 which communicate with radiators 16 through valve fittings 17. The heated liquid passes from the radiators 16 by way of pipes 19 which discharge into branch return pipes 20 connected to a main return pipe 21 arranged to discharge into the lower part of the heating unit 10.

In addition to the above described apparatus for heating the building, I have provided a hot water supply tank at 22 to which hot water is supplied through a pipe 23 communicating with a coil disposed in the heating unit 10 and hereinafter described. The lower end of the hot water supply tank 22 communicates with the coil through a pipe 24. Leading from the upper end of the tank 22 is a pipe 26 through which water may be delivered to any desired number of faucets (not shown), or the equivalent, and projecting into the tank 22 is a pipe 27 through which water is delivered to the tank from a water main or the equivalent.

Referring now to Figs. 2, 3 and 4, it will be noted that my improved heating unit 10 comprises a substantially cylindrical shell 30 which is provided with an upper cover plate 32 and has its lower end closed by a plate 33. The plate 32 is preferably secured to an angle iron 34 by means of bolts 36, or the equivalent, the angle iron being preferably welded to the shell 30. The plate 33 is preferably welded to the inner surface of the shell 30, as best shown in Fig. 4. The outer surface of the shell 30 is preferably covered by a layer 31 of heat insulating material such as asbestos or the equivalent. A similar layer 31^a is provided upon the cover plate 32. Any suitable means may be provided for supporting the shell 30 and the apparatus contained therein, but I prefer to provide a fabricated base 33^a having legs 33^b.

Mounted upon the cover plate 32 are a plurality of binding posts or electrical terminal devices 37 and 38, which are electrically connected to electrodes 39 and 40, respectively, disposed within the shell 30. The electrical terminal devices 37 and 38 are substantially identical in construction and for this reason it will only be necessary to ex-

plain the details of one of them. Thus, in Fig. 8 I have shown the electrical terminal device 37 in section and it will be noted that it comprises a metallic screw-threaded 5 post 41 extending through a sleeve 42 formed of any suitable electrical insulation such as porcelain. The sleeve 42 extends through one of a plurality of apertures 44 provided in the cover plate 32 and the joint 10 between the sleeve and the cover plate is preferably packed with asbestos rings 45, or the equivalent. Disposed around the upper end of the sleeve 42 is a collar 47 and disposed around the lower end of the sleeve is a second 15 collar 48, the collars 47 and 48 being formed of any suitable electrical insulation. It will be noted that the lower end of the collar 47 and the upper end of the collar 48 engages the asbestos rings 45. Seated upon 20 the upper end of the collar 47 is an asbestos ring 50 and engaging the lower end of the collar 48 is an asbestos ring 51. Engaging the upper surface of the asbestos ring 50 is a metallic washer 54 and screw-threaded 25 upon the upper end of the rod 41 are a plurality of metallic nuts 55. This construction permits an electrical conductor to be readily secured to the upper end of the rod 41. A metallic washer 57 disposed upon the 30 lower end of the rod 41 cooperates with nuts 58 screw-threaded upon the rod to clamp the electrode 39 to the rod.

As best shown in Figs. 5 and 6, the electrodes 39 and 40 are substantially identical 35 in construction and each is substantially U-shaped in form, the electrodes being provided with apertures 60 to permit them to be coupled to the electrical terminal devices 37 and 38. The electrodes are formed of sheet 40 metal in this embodiment of the invention. It will be noted that the electrodes 39 and 40 are widest intermediate their ends and that they taper down to a relatively small size at their lower ends. I preferably employ 45 this construction as it facilitates the flow of a relatively large electrical current when the shell 30 is substantially filled with water and it enables the unit to operate satisfactorily on a relatively small current 50 when the level of the water in the shell is lowered by vapor pressure as hereinafter explained. The lower ends of the electrodes are provided with aligned apertures 61 to hold a porcelain or glass rod 62, or the 55 equivalent, porcelain or glass insulators 64 being mounted upon the rod 62 to accurately space the ends of the electrodes. Longitudinal displacement of the glass rod 62 is prevented by means of wires 65 twisted 60 around the ends of the rod.

Welded to the under side of the cover plate 32 is an annular channel shaped member 67 which communicates through the cover plate with a pipe fitting 68 also welded to the 65 cover plate. It will be noted that the lower

end of the pipe fitting 68 is substantially oval in shape to conform to the dimensions of the channel shaped member 67. The aforementioned pipe 11 is secured in any suitable manner to the pipe fitting 68 and depending from the channel shaped member 67 are a plurality of pipes 70 which preferably extend below the lower ends of the electrodes 39 and 40. It is readily understood that liquid may pass from the interior of the shell 30 up through the pipes 70 and thence into the channel shaped member 67 to be discharged through the pipe fitting 68. 75

Surrounding the pipes 70 is a coil 72, the lower end of which extends through the bottom plate 33 and is screw-threaded for connection to the aforementioned pipe 24. The upper end of the coil 72 preferably extends through the cover plate 32 and is screw-threaded for connection to the aforementioned pipe 23. The aforementioned return pipe 21 preferably communicates with the interior of the shell 30 through a tubular fitting 73 welded to the shell, and welded to the lower end of the shell 30 is a tubular fitting 75 adapted to receive the lower end of a pipe 76 which connects the improved heating unit with an expansion tank 77 disposed in the building above the radiators 16. 95 In the illustrated embodiment of the invention, the pipe 76 communicates with the pipe 11 through a pipe 78. I preferably provide a water gauge 80 which is operatively connected to the shell 30 by pipe couplings 81 welded to the shell. Water may be supplied to the system through a pipe 79 connected to a water main (not shown) or the equivalent. In this instance, the pipe 79 communicates directly with the heating 105 unit 10 but in other instances I may have it discharge into the return pipe 21.

The operation of the above described apparatus is substantially as follows: Assuming that there is a sufficient supply of water in the system and that the apparatus has not been in operation for some time, the shell 30 will be entirely filled with water. If the electrodes 39 and 40 are then connected to a suitable source of electrical energy (not shown) a current will pass through the water within the heating unit and the heat generated because of the resistance of the water will rapidly cause a portion of the water to vaporize. It is understood, of course, that a relatively large current will pass through the water when the electrodes 39 and 40 are entirely immersed therein. The pressure produced within the shell 30 will cause water to surge out of the shell by way of the pipe 110 76 which delivers it to the tank 77. Of course, the water may also pass up through the pipes 70 into the annular member 67 and thence through the pipe 11 to the radiators 115 which are at a lower elevation than the tank 120 125 130

77. The head of water is, of course, equal to the pressure obtaining within the shell 30 and it is this feature of the improved apparatus that permits it to function substantially automatically, for, as the supply of water in the shell 30 diminishes, less current will flow between the electrodes 39 and 40. During the operation of the heating unit some point of equilibrium will be reached whereat the water within the shell 30 will assume a substantially stationary level and the current passing between the electrodes will be of a substantially constant value. This condition will then obtain until water is withdrawn from the tank 22 through the pipe 26 or some other change occurs in the system.

It is readily understood that when the apparatus is functioning, a thermo-siphon action takes place which causes water to flow up through the tubes or pipes 70 into the pipe 11 by way of the chamber in the annular member 67. This water is distributed to the radiators 16 and then returns through the pipe 21 to the heating unit. The water passing up through the pipes 70 is heated by the vapor produced in the shell 30 by the electrodes 39 and 40, there being an exchange of heat through the walls of the pipes 70.

It is also readily understood that when the water within the shell 30 is heated in the manner set forth above, the water contained in the coil 72 is also heated and a thermosiphon action takes place to deliver the heated water to the hot water supply tank 22 by way of the pipe 23, cold water from the supply tank being delivered to the lower end of the coil 72 by way of the pipe 24.

40 In Fig. 1 I have diagrammatically illustrated conductors 85 and 86 connected to the electrodes 39 and 40, respectively, and to the terminals of a double pole switch 87 which is connected by conductors 89 and 90 to mains 91 and 92, the mains 91 and 92 being connected to any suitable source of electrical energy not shown. Obviously, when the switch 87 is closed, current will flow between the electrodes 39 and 40 if they project into the water.

50 I have illustrated a thermostat 95 of any suitable construction which may be positioned in any desirable room of the building and may be of any suitable construction, the arrangement being such that when the temperature within the room rises above a predetermined value, the thermostat functions to close a valve 97 provided in the pipe 11. This prevents the water heated within the shell 30 from passing up through the pipe 11 to the several radiators 16, and as the heated water is retained within the shell, the pressure therein will rise and cause the level of the water in the shell to fall. A 60 smaller current will then flow between the

electrodes 39 and 40 and less heat will be generated within the heating unit. If the room temperature falls below the predetermined value, the thermostat 95 functions to open the valve 97 and the water within the shell 30 assumes a higher level, permitting a larger current to flow between the electrodes 39 and 40 to generate more heat. Also, there will be a more or less rapid exchange of heat between the water within the shell 30 and the water contained in the coil 72 when any considerable quantity of water is withdrawn from the hot water supply tank 22, and the level of the water within the shell will rise to permit a larger current to flow between the electrodes.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A heating unit comprising a receptacle for holding a quantity of water, a plurality of electrodes positioned to project into the water, tubular means positioned to project into the water, said tubular means communicating with the interior of the receptacle, means communicating with said tubular means for supplying heated water by means of fluid pressure created within said receptacle to heating apparatus disposed outside of the receptacle, means for returning the water to the receptacle, and means for connecting the receptacle to an expansion tank.

2. A heating unit comprising a receptacle for holding a quantity of water, a plurality of electrodes mounted on the receptacle to project down into the water, a chamber in the upper end of the receptacle, means whereby the chamber communicates with the lower part of the receptacle, said chamber having a discharge outlet and said receptacle having an inlet opening whereby water discharged from said discharge outlet may return to the receptacle, and means for connecting the receptacle with an expansion tank.

3. An electrically operated heating device comprising a receptacle for holding water, a plurality of electrodes projecting down into the receptacle, a plurality of tubes arranged in the receptacle having openings in the lower part of said receptacle, means for operatively connecting said tubes to heating apparatus, means for connecting the receptacle to a return pipe, and means for connecting the receptacle to an expansion tank.

4. In apparatus of the kind described and in combination, a receptacle for holding

water, electrodes projecting into the receptacle, heating apparatus spaced from the receptacle, means for operatively connecting the receptacle to the heating apparatus, 5 means for returning water from the heating apparatus to the receptacle, an expansion tank connected to the receptacle, and automatic means for controlling the flow of liquid from the receptacle to the heating 10 apparatus by varying the pressure within the receptacle.

5. In apparatus of the kind described and in combination, a receptacle for holding water, electrodes projecting into the receptacle, heating apparatus spaced from the receptacle, means for operatively connecting the receptacle to the heating apparatus, means for returning water from the heating apparatus to the receptacle, an expansion tank 15 connected to the receptacle, and means including a thermostat for controlling the flow of liquid from the receptacle to the heating apparatus by varying the pressure within the receptacle.

of liquid from the receptacle to the heating apparatus by varying the pressure within the receptacle.

6. In apparatus of the kind described and 25 in combination, a receptacle for holding water, electrodes projecting into the receptacle, heating apparatus spaced from the receptacle, means for operatively connecting the receptacle to the heating apparatus, 30 means for returning water from the heating apparatus to the receptacle, an expansion tank connected to the receptacle, and means including a thermostat for controlling the 35 temperature of the liquid in said heating apparatus by permitting a variation of fluid pressure within said receptacle and a consequent variation in the effective area of the electrodes.

In testimony whereof, I have hereunto 40 signed my name.

RICHMOND ROCHESTER, JR.
